Aaron L. Applebaum

UNITED STATES PATENT OFFICE.

ORESTE RICCI, OF BROOKLYN, NEW YORK.

AUTOMATIC DISPENSING DEVICE.

Application filed November 2, 1926. Serial No. 145,896.

This invention relates to automatic dispensing devices and more particularly to a novel and improved receptacle and hopper including a delivery mechanism for serving a toothpick, match or similar object.

One of the objects of my invention is to provide a dispensing device, manually operable and automatic in its function, constructed and arranged to simultaneously open the cover or closure of a receptacle or hopper to dislodge a toothpick, match or similar object from a supply and to present or serve the same and close the said cover or closure.

A further object of my invention is to provide an automatic dispensing device of the character above specified in which a supply of toothpicks, matches or similar objects may be confined and concealed within a receptacle or hopper whereby they may be dispensed and served individually, the operating mechanism being concealed and the said receptacle or hopper being removable so as to replenish the same with the objects being dispensed.

To enable others skilled in the art to more fully comprehend the underlying features of my invention that they may embody the same in the many uses and practical applications and purposes to which it may be employed, drawings depicting a preferred form thereof are annexed hereto as part of my disclosure in which

Fig. 1 is a side view of the dispensing device, a portion of the operating mechanism being shown in dotted lines.

Fig. 2 is a top plan.

Fig. 3 is a sectional view taken on the line 3—3 of Fig. 2 and showing the operating mechanism.

Fig. 4 is a sectional view taken on the line 4—4 of Fig. 2.

Referring now to the drawings wherein like reference characters designate corresponding parts throughout the several views, 45 illustrates a substantially rectangular frame having corner supporting legs 6 and constructed preferably of stamped metal. The frame supports a casing 7 which may be of various designs and in the form shown 50 representing a boat body having front and rear depending extensions 8, 9 which are rigidly attached to the frame.

The rear extension 9 is provided with a slot therethrough for the passage of a bent link 10 extending through the frame, said link being pivotally connected at 11 to one

end of a Y-shaped lever 12 below the said frame. The lever 12 is provided with upwardly directed ears 13 and pivotally mounted on a pin 14 held by a bracket 15 secured permanently to the bottom surface of the frame. The pin 14 also provides means for retaining a coil spring 16 which normally depresses the lever 12 to the position shown by Fig. 1 of the drawing.

It will be noted that the lever 12 is pivotally supported off center and is substantially concealed by the frame. The forward end of the lever is formed with two branches 17 to which are attached the vertical rods 18 held thereto by the nuts 19, said rods passing through slots 20 of the frame and further provided with the finger buttons 21 whereby the said lever may be actuated against the resistance of the spring from either side of the frame.

The upper end 22 of the bent link 10 is pivotally connected to a toggle 23 having bearings 24 rotatable on a stationary shaft 25, said shaft being mounted in suitable bearings between the sides of the casing or boat 7. Formed with the toggle 23 or one of its bearings 24, I provide a curved, segmental, cover actuating element 25^a which extends upwardly and forwardly to engage the outwardly bent end 26 of a rod 27.

Within the casing 7, there is provided a hopper or receptacle 28 shaped to conform with the interior thereof and in which the particular objects to be dispensed are confined and which may be toothpicks, matches or other light, similar objects. The hopper or receptacle may be removed from the casing so as to replenish the supply of the objects to be dispensed, said hopper being securely held in the casing by suitable pins 29 passing through openings in the said casing. The rear end of the hopper 30 is closed but the front end thereof open so that when the hopper is removed, the toothpicks or matches may be introduced therein through the open end.

As further shown by Figs. 2 and 3 of the drawing, the top of the hopper is equipped with a hinged cover or closure 31 having pintles 32 connected to the rod 27 whereby when the latter is actuated by the actuating element 25 the said cover may be opened. A spring 33 also mounted on the rod and bearing against the rear edge of the cover normally maintains the same closed. The said cover is also provided with a lip

34 whereby it may be raised by the finger if so desired and a quantity of the objects introduced into the hopper without removing the same from the casing.

11 The toggle also supports the legs 35 of a dispensing device 36 which as shown simulates a bird or animal thus producing an ornamental feature to the device, the head or bill 37 of which is equipped with a 16 spring clamp 38 which is adapted to engage a toothpick, match or similar object in the hopper when the lever is depressed from the position shown by Fig. 1 to that shown by Fig. 3 of the drawing. In other words, the actuation of the lever and link mechanism projects the dispensing device 36 so that it moves in a segmental path is effected simultaneously with the opening and closing of the cover or closure of the hopper.

26 Having shown and described my invention what I now claim as new and desire to secure by Letters Patent of the United States is:

1. A dispensing device of the class described comprising a frame, a removable hopper mounted on the frame, a closure for said hopper, an object gripping element located exteriorly of the hopper, lever operating means pivoted below the frame for actuating said gripping element for movement in a path within one end of the hopper, means for opening said closure at one end thereof in advance of the movement of the gripping means wherby one or more objects may be automatically withdrawn from a group positioned in said hopper.

2. A dispensing device of the class described comprising a frame, a casing on the frame, a hopper within the casing, a closure for said hopper, an object gripping element pivotally mounted in one end of the casing and exteriorly of the hopper, a lever pivoted to the frame, a connecting link between said lever and the object gripping element for actuating the same in an arcuate path for movement within one end of the hopper and open said closure whereby one or more objects may be automatically withdrawn from a group positioned in said hopper.

3. A dispensing device of the class described comprising a frame, a casing on the

frame, a removable hopper within the casing, a resiliently held hinged closure for the hopper, an object gripping element pivotally mounted in one end of the casing and exteriorly of the hopper, a resiliently controlled lever pivoted to and below the frame, a connecting link between said lever and the object gripping element for actuating the same in an arcuate path for movement within one end of the hopper and means carried by said gripping element to engage the hinge of the said closure whereby the latter may be opened in advance of the said element to permit one or more objects to be automatically withdrawn from a group positioned in said hopper.

4. A dispensing device of the class described comprising a frame, a casing on the frame, a removable hopper within the casing, a hinged closure for the top of the hopper, a shaft in one end of the casing, an object gripping element pivotally mounted on said shaft, a resiliently controlled lever pivoted to the frame, a link connecting said lever and the object gripping element whereby the latter may be actuated in an arcuate path for movement within one end of the hopper, and a segment carried by the object gripping element for actuating the hinge of the closure at one end thereof to open the latter whereby one or more objects may be automatically withdrawn from a group positioned in said hopper.

5. A dispensing device of the class described comprising a frame, a casing on the frame, a hopper within the casing, a closure for said hopper, a shaft in one end of the casing, an object gripping element pivotally mounted on said shaft having resilient means for engaging one or more objects within the hopper, a resiliently held lever pivotally mounted below the frame, a connecting link between one end of the lever and the object gripping element and means for operating the lever from either side of the frame whereby the object gripping element may be actuated in an arcuate path within one end of the hopper and means for simultaneously opening the closure as the object gripping element is so actuated.

In testimony whereof I affix my signature.
ORESTE RICCI.
